UNITED STATES PATENT OFFICE.

ALEXANDER H. HILL, OF OSKALOOSA, IOWA.

REVOLVING SHOW-CASE.

SPECIFICATION forming part of Letters Patent No. 244,600, dated July 19, 1881.

Application filed May 2, 1881. (No model.)

To all whom it may concern:

Be it known that I, ALEXANDER H. HILL, of Oskaloosa, in the county of Mahaska and State of Iowa, have invented certain new and useful 5 Improvements in Revolving Show-Cases; and I do hereby declare that the following is a full, clear, and exact description thereof, reference being had to the accompanying drawings, and to the letters of reference marked thereon, which form part of this specification, in which—

Figure 1 is a side elevation of my show-case. Fig. 2 is a horizontal section of the same. Fig. 3 is a central vertical section, and Figs. 4 15 and 5 are enlarged detail views of the rollers.

My invention relates to revolving showcases; and it consists in the peculiar combination and arrangement of parts, whereby they may be more conveniently operated, singly or 20 together, as will be hereinafter more fully set forth.

In order to enable others skilled in the art to which my invention appertains to make and use the same, I will now proceed to describe 25 its construction and operation.

The frame of my device consists of the circular top and bottom plates, A A', connected by the upright posts or supports A². The top and bottom plates, A A', are each provided 30 with two concentric grooves, a a, in which slide the curved sideframes, B B B, said side frames or sash being filled with glass in order to fully expose to view the goods, and at the same time prevent dust from getting at them. By 35 this arrangement any desired part of the case may be reached without turning it by pushing aside one of the panels or sash B, which should slide easily in the grooves a a.

The interior of the case is provided in the center with an upright stationary post, C, having its ends secured in the top and bottom pieces, A A', and upon this post are located the top, bottom, and center plates, as seen in Figs. 1 and 3, the two latter for displaying the goods. 40 These three circular plates, D D D, are connected by uprights or supporting-posts d d d, and between the bottom and center plates are a series of rollers, E, arranged in triangular form, their ends being journaled in the uprights d d d. 45 These rollers, intended for the display of silks, 50

ribbons, or similar goods, are made in two pieces, which may be connected at their ends by screws or by ferrules e e, as I have shown them in the drawings. One end of the rollers enters a recess, e², in one of uprights d, which 55 also contains a spiral spring arranged to press against the roller, and tends to push it outward. The other end of the rollers enters a hole, e', passing through the opposite upright or post d, and is provided upon its end with a clutch, e³, for the purpose presently indicated.

f is a knob, having a projecting pin or stud, f', upon its inner face, provided with an annular groove, f². The stud f' enters the hole e', and is held in place and allowed to revolve by 65 a pin passing through the side of the upright d and its point entering the annular groove f². The inner end of the stud or pin f' is formed with a clutch, f³, corresponding to and engaging with the clutch e³ on the end of the roller E. 70 By this means the roller may be readily turned with the knob to roll or unroll the goods to be displayed, and by pressing the roller endwise against the spring the opposite end becomes freed from the clutch and upright, and may be 75 readily removed for the attachment or detachment of the goods.

If desired, the recesses in the uprights d d may have metal linings, to prevent undue wear of the rollers and their bearings. 80

The goods are attached to the rollers by being clamped between the two parts, as seen in Fig. 5 of the drawings.

Upon the shaft or post C, above the center plate, D, are arranged a series of shelves, F, 85 which may be adjusted up or down, as desired, by means of collars g, upon which they rest, these collars being secured to the post at any point by set-screws g'.

When the interior frame is revolved it carries with it the series of rollers and the shelves; but either of the latter may be revolved singly, if desired, as they are loose upon the central post; or the shelves may, if found desirable, be supplied with spring-pawls, by 95 means of which they may all be revolved together in one direction, or any of them may be revolved alone in the opposite direction.

The bottom plate, D, is provided upon its under side with one or more drawers, G, for 100

holding spools of thread, buttons, braid, or any small articles ; but, if desired, these drawers may be suspended from a separate plate, so they may be revolved at will without moving the other parts of the display-frame.

The show-case thus made is cheap, convenient, not liable to get out of order, and may be easily taken apart for shipment by removing the screws securing the uprights of the frame to the top and bottom plates, and may then be packed in small compass.

Having thus fully described my invention, what I claim as new, and desire to secure by Letters Patent, is—

15 1. In a show-case, the combination, with a stationary center post, of a triangular revolving frame consisting of the plates D D D, uprights d d, and rollers E, and a series of inde-

pendently - revolving shelves, F F, all constructed and arranged to operate substantially as and for the purpose set forth.

2. A show-case consisting, essentially, of the outer frame, A A' A², having concentric grooves a a and sliding panels B B, and the inner revolving frame, D d, having divided show-rollers E and independently-revolving shelves F, all constructed and arranged to operate substantially as and for the purpose set forth.

In testimony that I claim the foregoing as my own I affix my signature in presence of two witnesses.

A. H. HILL.
